ATTORNEY

UNITED STATES PATENT OFFICE.

HERMAN G. LORENTZ, OF CROMWELL, CONNECTICUT, ASSIGNOR TO THE J. & E. STEVENS COMPANY, OF CROMWELL, CONNECTICUT, A CORPORATION OF CONNECTICUT.

JAR-CAP REMOVER.

Application filed June 8, 1922. Serial No. 566,726.

To all whom it may concern:

Be it known that I, HERMAN G. LORENTZ, citizen of the United States, residing at Cromwell, in the county of Middlesex and 5 State of Connecticut, have invented certain new and useful Improvements in Jar-Cap Removers, of which the following is a specification.

This invention relates to a jar cap-remover. It is a matter of fact that there is 10 at present in everyday use a jar which has a cap usually of glass, which is held clamped down to the body of the jar by spring means which are opened to permit the removal of 15 the cap. It is a further fact that very often this cap sticks to such an extent that it becomes an exceedingly difficult matter to take it off, this being due to the presence of a vacuum within the jar by which the cap is 20 caused to tightly adhere to the body of the jar. It is the primary object among several, to provide a device of the character set forth which can be quickly associated with a jar and its cap, which is light yet strong, occupies 25 but a small space, and which when properly manipulated can bring about or initiate the instantaneous removal of the cap.

The invention possesses other features of 30 novelty and advantage which with the foregoing will be set forth at length in the following description wherein I will outline in detail that one of the several embodiments of the invention which I have selected for 35 illustration in the drawing accompanying and forming part of the present specification. Clearly, I am not restricted to the exact disclosure made by said drawing and description.

40 Referring to said drawing:

Fig. 1 is a top plan view of a jar cap remover involving the invention.

Fig. 2 is a side elevation of the same, the dotted lines showing the action of the device.

45 Fig. 3 is a side elevation on a smaller scale of a jar showing the article in position.

The device involves in its make-up a body portion which is adapted to and is furnished with means by which it can be detachably 50 associated with a jar in a ready manner, this body portion being provided with means by which the vacuum to which I have already alluded can be instantly broken and if necessary the vacuum breaking member of what-

ever character it may be can be utilized to 55 initiate the lifting of the cap from the body of the jar.

As shown, the body portion is denoted in a general way by 2, being practically in the form of a yoke or bail and comprising the 60 elongated shank 3 and the pendant arms 4 and 5 which as shown are at the ends of the shank 3 although in all cases this may not be necessary, nor am I restricted to the shape of the body portion or bail 2 represented. 65

I have shown a jar 6 which is adapted to contain fruits, vegetables or other articles and the body of which has a cap 7 which is the purpose of the implement constituting the subject matter of the present case to 70 remove or at least to break the vacuum between the same and the body of the jar to facilitate such removal. As shown, the arm or projection 5 has in adjacence to its lower end a lug or ear 8 of somewhat arcuate form 75 and an edge practically of knife form.

As represented, the vacuum breaking member is a screw 9 threaded through the arm or projection 4 near the lower end thereof. The operative or inner end of the 80 screw is shown pointed as at 10, the head of the screw at the outer end being designated by 11. The screw 9 is virtually opposite the lug or ear 8.

In action, the article will be caused to 85 straddle a capped jar with the arms 4 and 5 diametrically opposite each other and with the shank 3 extending diametrically of the cap 7. The lug or ear 8 will be inserted desirably under the cap 7 and the screw 9 will 90 be advanced so that the cone pointed end 10 thereof will be forced under the opening between the cap 7 and the body of the bottle. This action results in instantly breaking the 95 vacuum so that the cap 7 can be if desired lifted off by hand.

The shank or main part 3 may have if desired through it a slot 12 to receive the knob or protrusion upon the central part of the jar cap 7 when present. 100

I find that the shank 3 when constructed as shown is one possessing the maximum strength. The sides of the shank diverge from one end to the other and are of ogee or compound curved form. They are provided 105 on their upper sides with ribs or beads 14 which meet each other at the end of the shank near which the screw 9 is located.

These ribs are of ogee formation to conform virtually to the shape of the sides of the shank. At the butt the shank has a slot 15 beneath which the lug or ear 8 is located.

5 What I claim is:

A jar cap-remover comprising a body having arms at its ends which extend downwardly therefrom, the shank of the body having an arcuate slot at an end portion 10 which extends through the adjacent end arm, the slotted arm being furnished at its lower end with a bevelled lug which is adapted to find a bearing against the jar and a screw threaded through the complementary arm, the 15 inner end of the screw being of cone point

formation, and in line with the bevelled edge of said lug, the shank part of the body having an approximately central slot, and the sides of said body converging toward that end thereof which is equipped with the 20 screw, the upper side of the body having flanges thereon which follow the contour of the sides of the body.

In testimony whereof I hereby affix my signature.

HERMAN G. LORENTZ.
